UNITED STATES PATENT OFFICE

ELMER R. POPE, OF HAMILTON, MASSACHUSETTS, ASSIGNOR TO UNITED SHOE MACHINERY CORPORATION, OF PATERSON, NEW JERSEY, A CORPORATION OF NEW JERSEY

HEEL-ATTACHING MACHINE

Application filed July 31, 1928. Serial No. 296,559.

This invention relates to machines for nailing heels to shoes, and is especially concerned with nail-driving elements of the apparatus.

In a common form of machine chiefly employed for the attachment of wood heels from the insides of shoes and known as the Alpha wood heel nailing machine, the drivers operate in openings in a work-supporting jack and insert the attaching nails so that their heads lie at or just below the surface of the insole. It is of considerable importance that this action shall be reasonably uniform, so the nails will not be driven too little and thus contact with the foot of the wearer of the shoe, or too much, unduly indenting the insole. An adjustment is therefore provided for the drivers, they being threaded into their carrier and fixed in their adjusted relation by lock-nuts or set-screws. An object of this invention is to reduce the time required for the operator to make such adjustments. This I accomplish by providing a member common to a plurality of the drivers for retaining them against movement in the position to which they may be longitudinally adjusted. A single movement of this retaining member either releases or secures any number of drivers upon their carrier, whereas with set-screws or lock-nuts, a separate operation would be necessary for each. As herein illustrated, a plate is employed, resting normally upon the top of the driver-carrying head and having a locking opening for each driver. The lifting of the plate frees all the drivers for adjustment, and its release causes them to be locked against rotation.

For various reasons, it may be desired to give the operating ends of the drivers of heel-attaching machines forms which are asymmetric with respect to their longitudinal axes. An example of this is furnished by the inclining of the driver-surfaces which contact with the inserted nails to cause said nails to converge toward the axis of the heel to be attached, and thus permit them to be driven closer to the rand-crease. Another object of my invention is to maintain the correct relation of the driver-end formation to the jack and work. This I attain through the pro-

vision of means which releasably fixes each driver against rotation in its carrier, with the end formation in a predetermined angular relation. This means may include a projection from the driver, fixed in its angular relation to the inclined end or other asymmetric formation, and such a locking means as a plate having an opening through which the driver passes and an extension from the opening to receive the projection, the extension, as well as the projection, having a predetermined angular relation to the inclined surface. The projection and opening-extension can only co-operate when the driver-end is correctly positioned. This plate may be utilized as the locking means for the drivers of the entire gang upon the carrier.

The drivers are adjusted, as already indicated, by virtue of their threaded mounting upon their carrier. They are rotated to effect the adjustment by a tool entering the openings in the block in which the drivers move and engaging their ends. A screw-driver engaging a slot in the operating end of each driver may be utilized, but tends to give trouble because of its liability to displacement from the slot. A further object of this invention is to facilitate the driver-adjustment. This I accomplish by forming at one side of each driver-end a space furnished by a segment removed from the driver at one side of the longitudinal axis. This space is thus adjacent to the wall of the opening in the jack-top or other block in which the driver moves. With the drivers having inclined ends, as herein disclosed, this space is preferably at the lower side of the incline. With such an end-formation, a tool may be used which has a body fitting the jack-opening and a projection complementary to the driver-space. An arrangement of this character causes the projection of the tool to seat itself naturally in the space and effectively resists accidental displacement. The driver-end also presents a maximum unbroken surface for engagement with the nail-heads.

In the accompanying drawings,

Fig. 1 shows in vertical section the jack of a heel-attaching machine to which one form of my invention is applied;

Fig. 2 is a similar view, with the drivers in their normal positions and with the locking plate raised for adjustment;

Fig. 3 is a horizontal section on the line 5 III—III of Fig. 1;

Fig. 4 is a sectional detail of a portion of one of the drivers in its opening with the adjusting tool being brought into co-operation with it; and

Fig. 5 is a like view, with the tool seated for the adjusting operation.

A jack-body 10 carries upon it a top or die-block 12, in the vertical nail-receiving openings 14 of which operate cylindrical drivers 16. These drivers are preferably threaded at 17 into a plate 18 carried upon a head or plunger 20 guided within the hollow body of the jack. To the head is joined a spindle 22, to which power is applied to 15 reciprocate the drivers for the insertion of the nails N, which they bear upon their upper extremities, through the heel-seat of a shoe S into a heel H to be attached. In this nail-inserting travel, the drivers move from their 20 lowest point, as illustrated in Fig. 2 of the drawings, to one shown in Fig. 1, in which their operating ends are at or just above the curved work-supporting surface 24 of the jack-top. To cause the nails to be driven inclined inwardly from the heel-seat toward the longitudinal axis of the heel, the upper extremities of the drivers may be oppositely inclined at 26, or upwardly and outwardly from the axes of the jack and heel. The end of 25 each driver is therefore asymmetric with respect to its longitudinal axis. This tips the points of the nails in, so, as they emerge from the openings 14, they tend to follow the paths indicated in Fig. 1. Nails thus driven may 30 be placed relatively close to the rand-crease without their points emerging through the side wall of the heel. A tight crease is thus obtained.

To originally produce the correct relation 45 of the drivers to the jack-top, or to adjust them vertically to compensate for wear, they may be raised and lowered by turning them in their threaded engagement with the plate 18. To prevent rotation of the drivers, and 50 thus retain them in adjustment, there is provided a locking means, preferably common to all. Just above the upper surface of the plate 18, each driver has a projection 28. Normally resting by gravity upon the driver-plate is a locking plate 30, through which 55 is a circular opening 32 to receive each driver, and a lateral extension 34 from each opening, which the corresponding projection 28 may enter. The angular relation of the inclined driver-surfaces 26, the driver projections 28 and the locking extensions 34 is such that, when the projection is secured by being 60 within the extension, the surface 26 is correctly inclined with respect to the vertical axis of the jack and the heel to be attached.

To permit the drivers to be turned, the plate 30 is raised, as appears in Fig. 2 of the drawings. This frees the projections 28, and any or all of the drivers may be rotated in their threaded connection 17 to bring their upper ends to the desired levels. With the projections brought into alignment with the opening-extensions 34, the release of the plate 30 causes the extensions to again receive the 70 projections and lock the entire driver-gang. This gang may consist not only of those arranged according to a single nailing design, such as is illustrated in the drawings, but also series for one or more other designs when multiple drivers are used. Such a second set of locking openings 32 is shown.

To turn the drivers, they are most conveniently engaged by a tool applied to their upper ends through the jack-openings 14. For this purpose, a segment, preferably less in extent than half the upper surface of each driver-end, is cut away at 36, this being shown as at the lower side of the inclined surface 26. This end-formation is adapted to cooperate with such a tool as appears in 80 Figs. 4 and 5. A handle 40 carries a stem 42, upon which is a head 44. This head is complementary to the driver-end, having a cylindrical portion fitting the jack-openings 14, with a surface 46 inclined oppositely to the driver-surface 26 and substantially equal in size thereto. A projection 48 from the body is adapted to enter the space 36 in the driver. The body 44 is inserted within a jack-opening 14, in the manner illustrated 90 in Fig. 4, and is lowered and turned until the projection 48 seats itself in the space 36. This engagement is readily effected, and, being obtained, the tool is locked in place against displacement until it is lifted vertically. For application to drivers when their ends are outside the jack-top, as at the time of their application to the plate 18, the driver and tool may be maintained in operating 100 alignment by a sleeve 50 surrounding the stem and having an annular space 52 to receive the head 44 and the driver-end. This co-operation is particularly shown in Fig. 5. In this way, the tool is as effectively maintained in alignment with the driver as when 110 it is within the jack-opening. It is to be noted that, with the segment removed at 36 from the inner side of the driver-end and at the bottom of its incline, there is given, as a nail tips inwardly upon the driver, a substantially unbroken surface for engagement with a nail-head. This is less liable to mutilation than would be an end divided, for example, across the center, as by a screw-driver-slot.

Having described my invention, what I claim as new and desire to secure by Letters Patent of the United States is:

1. In a heel-attaching machine, a carrier, 120 drivers adjustable longitudinally upon the

carrier, and a member common to plural drivers for releasably retaining them against movement in their adjusted positions.

5 2. In a heel-attaching machine, a carrier, drivers threaded into the carrier, and a member common to plural drivers and arranged to prevent their rotation in the carrier or to free them for adjustment.

10 3. In a heel-attaching machine, a carrier, plural series of drivers adjustable upon the carrier, each series corresponding to a particular nailing design, and a member arranged to lock simultaneously in their adjustment the drivers of plural designs.

15 4. In a heel-attaching machine, a reciprocating head, a gang of drivers threaded into the head, and a plate having a locking opening for each driver of the gang.

20 5. In a heel-attaching machine, a reciprocating head, a gang of drivers threaded into the head and each provided with a projection, and a plate having locking openings respectively arranged to receive and retain against rotation the projections from the drivers.

25 6. In a heel-attaching machine, a reciprocating head, a gang of drivers threaded into the head and projecting upwardly therefrom, and a plate normally resting upon the top of the head and arranged to lock the driver-gang against rotation and to be raised to free them for adjustment.

30 7. In a heel-attaching machine, a carrier, a driver mounted to rotate upon the carrier and having an end-formation asymmetric with respect to the longitudinal axis of the driver, means arranged to adjust the driver longitudinally of its axis, and means arranged to releasably fix the driver against rotation upon the carrier with its end-formation in a predetermined angular relation.

35 8. In a heel-attaching machine, a carrier, a driver mounted to rotate upon the carrier and having an inclined driving end, and means arranged to releasably fix the driver in one angular position only against rotation upon the carrier.

40 9. In a heel-attaching machine, a carrier, a driver mounted to rotate upon the carrier and having an inclined driving end, a projection having a predetermined angular relation to the inclined end, and locking means for the driver arranged to engage the projection.

45 10. In a heel-attaching machine, a carrier, a driver mounted to rotate upon the carrier and having an inclined end, a projection from the driver having a predetermined relation to the inclined end, and a plate having an opening through which the driver passes, said opening being provided with an extension to receive the driver-projection.

50 11. In a heel-attaching machine, a reciprocating head, a gang of drivers threaded into the head and each having an inclined driving end, and a locking member common to the

drivers of the gang and arranged to releasably fix them against rotation upon the head.

55 12. In a heel-attaching machine, a reciprocating head, a gang of drivers threaded into the head and each having an inclined driving end and a projection bearing a predetermined angular relation to the inclined end, and a locking plate provided with openings to receive the drivers of the gang and extensions from the openings in which the driver-projections normally lie.

60 13. In a heel-attaching machine, a jack having openings extending vertically, and reciprocating drivers operating in the openings, the ends of the drivers being inclined 80 downwardly and inwardly toward the axis of the jack and each having a segmental portion removed from the lower side of the incline.

65 14. In a heel-attaching machine, a shoe-support provided with a nail-receiving passage, a reciprocating head co-operating with the support, and a cylindrical driver adjustable in the head and operating in the support-passage, said driver having removed from its 85 nail-engaging end at one side of the longitudinal axis a segmental portion arranged to receive an adjusting device.

70 In testimony whereof I have signed my name to this specification.
